SCREW COVER WRENCH

Edgar H. Mattocks, Chicago, Ill.

Application October 23, 1944, Serial No. 559,988

4 Claims. (Cl. 81—3.42)

1

My invention relates to a wrench or device whereby the tightly sealed screw caps or covers of jars, cans, bottles and the like may be easily unscrewed and when desired again tightly screwed into firm sealing condition; the device being especially designed for domestic use.

My improved device or wrench, as it may be termed, is constructed to be easily adjusted to caps or covers of different sizes and a firm gripping relation effected without, however, marring or destroying the threaded condition of the cap or cover for further use.

Another object of the invention is the provision of a device which can be easily adjusted and put into cover gripping condition without need for separate tools; a device which can be readily manipulated by any one and sufficient leverage provided for the unscrewing or screwing operations.

The objects and advantages of my invention will all be readily comprehended from the following detailed description of the drawing wherein:

Figure 1 is a top plan view of my improved wrench, shown applied to a screw cap or cover.

Figure 2 illustrates my device in side elevation, applied to the screw cap or cover of a jar of which a portion of the upper neck end is shown.

Figure 3 is a bottom plan view of the device.

Figure 4 is a sectional top plan taken substantially on the line 4—4 of Figure 2, looking in the direction of the arrows.

Figure 5 is a cross sectional view taken on the line 5—5 of Figure 4.

In the particular exemplification of my invention, which is especially designed for household use, the wrench comprises a hand-grasping portion or shell 10, made of metal or any suitable rigid material, preferably of rectangular form and suitable length to afford the desired leverage and also provide proper slideway for the elements later to be described.

For purposes of illustration, the shell 10 is shown as a sheet metal blank whose longitudinal edges are bent back beneath the top, as at 11, 11 to provide a slideway for the cover or cap gripping elements which are adjustable lengthwise of the hand-grasping shell 10.

One of the cover grasping members consists of an elongated blank 12 adapted to slidably fit between the inturned flanges 11, 11 and slotted lengthwise as shown at 13, said slot terminating short of the ends. The outer end of the blank 12 is shown bent back beneath the top to form one of the cover or cap engaging jaws 14, which is

2

provided with an intermediate arcuate portion 15 and with the pointed portions or teeth 16, 16. The arcuate portion 15 is adapted to receive the arcuate surface of the cap or cover, while the teeth 16 adapted to engage the knurled perimeter of the cap or cover and prevent relative rotative movement between the jaw or member 14 and the cover or cap, which is shown at C, when the device has been placed in gripping condition.

One longitudinal side wall of the elongated slot 13 of member 12 is provided with the forwardly presented teeth 17, formed a predetermined distance from the outer end and extending toward the rear end of the slot 13, as shown in Figures 3 and 4.

Inserted in the slideway formed by flanges 11, 11, in sliding contact with member 12, is a jaw member 18, whose forward end is slightly offset downwardly so as to be disposed substantially in the same horizontal plane as the rearwardly presented toothed end 14 of the first mentioned jaw or gripping member 12. The offset forward end of member 18, similar to the end 14 of member 12, is provided with an intermediate arcuate portion 19 to engage the perimeter of the cap or cover, and with the forwardly presented pointed portions or teeth 20, 20 which are adapted to engage the knurled surface of the cap or cover C.

The body of the inner jaw member 18, at its longitudinal center, is provided with a circular hole 21 of predetermined size and adapted to receive the cam action rotatable disc 22, which is provided with an eccentrically arranged slot to receive the rectangular stem 23 of the finger-grasping member 24, so that rotation of member 24 will rotate the cam action disc 22 in the hole 21 of jaw member 18 and induce slight outward and/or inward movement of member 18.

Arranged in the slot 13 of jaw member 12, and disposed on the upper face of jaw member 18, is a dog or pawl 25, whose toothed end 26 is normally held in yielding engagement with the teeth 17 of jaw member 12 by a suitable spring 27 whose one end is secured to the pawl 25 while the other end may be secured to the cam action or eccentrically mounted disc 22; the spring 27 being adapted to yieldingly maintain the toothed end 26 of the pawl in engagement with the rack or teeth 17 of member 12.

The toothed end of pawl 25 is provided with a hole for free passage of the stem 23 of the finger grasping member 24, so that the latter may be rotated without imparting movement to the pawl 25; the hole in the pawl 25 being sufficiently large

to permit movement of the pawl independently of the stem 23.

The other end of pawl 25 is provided with an upstanding pin 28 which extends through a slot 29 arranged in the shell or casing 10; the pin 28 normally being disposed at one end of slot 29, through the action of the spring pressure on the pawl, namely in the position shown in Figure 1.

By reason of its mounting, the inner jaw member 18 has merely slight limited sliding movement in the shell or casing; whereas the outer jaw member 12 may be slid lengthwise of the shell or casing when the pawl 25 is moved out of contact with the teeth 17 of member 12, induced by forcing the pin 28 toward the opposite end of slot 29.

With the teeth 17 sloping forwardly as shown, outer jaw member 12 may be easily forced inwardly, as the teeth will ride over the pawl; while on the other hand outward movement of the member 12 is impossible until the pawl is manually moved against the action of spring 27 by pin 28.

In operation, the jaw end 14 of member 12 is held against one side of the screw cap or cover C, as shown in Figures 1 and 2 and the shell or casing 10 with inner jaw member 18 is then slid forward toward the outer end of member 12, until the arcuate, toothed end of member 18 is in contact with the side of the screw cap or cover, diametrically opposite the point of contact of outer jaw member 12; the free forward sliding of the casing and contained inner jaw being readily accomplished as hereinbefore stated.

In order to effect a firmer gripping relation between the jaws and the jar cap or cover, finger grasping member 24 is then partially rotated, causing the eccentrically mounted disc 22 (disposed in the hole 21) to force the outer end of member 18 into firmer binding relation with the cap or cover C, with the pointed portions or teeth 16, 16 and 20, 20 of both members in engagement with the usual knurled perimeter of the cap, so that movement of the shell or casing in proper rotative direction will cause the cap or cover C to readily unscrew.

It is apparent that the device could also be employed, if desired, for firmly screwing caps or jar covers into place by moving the handle or shell in the opposite or screwing direction.

The end of the stem 23 may be swaged or riveted to the cam disc 22, to maintain the various elements in assembled relation; or, as shown in Figures 3 and 5, I prefer to employ a separate disc or washer 30 with a central opening to receive the end of stem 23 which is riveted in place and as the washer is concentric with the stem it will not register with the hole 21 in member 18 because the hole 21, by reason of cam disc 22 will always be eccentrically disposed relative to stem 23 and washer 30.

I have shown and described what I believe to be a simple adaptation of my invention, but certain structural modifications are possible and may be made without, however, departing from the spirit of my invention as defined in the appended claims.

What I claim is:

1. A device of the character described comprising an elongated shell or casing open at the forward end; an elongated lengthwise slotted plate slidably mounted in the casing to extend beyond the end thereof and having its forward end bent rearwardly therebeneath to provide a jaw member, one wall of the slot in the plate hav-

ing longitudinally arranged teeth; a second jaw plate with an annular hole and slidably arranged in the forward end of the casing to extend therebeyond with its forward end formed to effect non-slip engagement with a screw cover and arranged in parallel supporting relation with the first mentioned slotted plate to permit the latter to slide thereon; rotative means operable from the casing exterior disposed through the casing, the slot in said first mentioned plate and the annular hole of the second jaw plate and provided with a cam member arranged in said annular hole in said second jaw plate whereby the second jaw plate is given predetermined restricted sliding movement when said means is rotated, to effect firm binding relation with the screw cover; means arranged at the lower end of said rotative means whereby the operative relation between said rotative means and the second jaw plate is maintained; a pawl pivotally supported on said second plate by said rotative means and arranged within the slot of said first mentioned plate; a spring whereby said pawl is normally held in engagement with said teeth and the first mentioned plate thereby held against outward movement; and means secured to said pawl and extending to the casing exterior whereby the pawl may be moved out of holding engagement with said teeth.

2. A screw cap wrench comprising an elongated casing open at the forward end and provided with a transversely disposed arcuate slot; an elongated plate member slidably mounted in the casing, slotted lengthwise and provided at its forward end with a rearwardly facing cap-engaging arcuate surface; a second plate member, arranged in the casing to slidably support the elongated plate, said second plate being provided at its forward end with a cap-engaging arcuate surface extending beyond the forward end of the casing and having a circular hole intermediate its ends; rotative finger operated means disposed through the casing and said circular hole; a cam member secured to said last mentioned means and arranged in said circular hole for controlling said second plate member and having cam action relation with the hole whereby rotation of said means will cause said plate to be shifted into firm gripping relation with the screw cap; pawl and rack mechanism arranged in the slot of the elongated plate to maintain operative relation between the two plate members whereby the cap-engaging portion of the first mentioned plate member is held against undesired outward movement; and means disposed through said arcuate slot in the casing whereby the pawl may be moved out of rack engaging position.

3. A screw cap wrench comprising an open ended casing; an elongated plate member slideable in the casing and provided at its forward end with rearwardly facing cap-engaging surfaces and with a series of forwardly presented teeth arranged lengthwise in the plane of said plate; a second plate member arranged in the casing to slidably support the elongated plate member and provided at its forward end with a cap-engaging surface extending beyond the forward end of the casing and with a hole intermediate its ends; a rotatable cam disc seated in said hole; a finger operated element disposed through the elongated plate and the casing and connected with said disc whereby said cam disc may be rotated and the second plate shifted into firm gripping relation with the screw cap when said cam disc is partially rotated; a spring controlled pivoted pawl carried by said second plate member

and normally engaging the teeth of said first mentioned plate member to hold the elongated plate member against outward sliding movement; and means associated with said pawl and extending to the casing exterior whereby the pawl may be moved out of holding engagement with said teeth and the elongated plate member permitted to slide outwardly.

4. A screw cap wrench of the character described comprising an elongated open ended casing provided with a transversely disposed slot; an elongated lengthwise slotted plate slidable in the casing with its forward end disposed beyond the casing and provided with a rearwardly disposed cap-engaging surface, one side wall of the elongated slot having a plurality of teeth; a second plate provided with a circular hole and arranged in the casing beneath and slidably supporting said slotted plate, the forward end of said second plate extending beyond the casing and provided with a cap-engaging surface; a spring controlled pawl arranged on said second plate within the slot of the first plate and normally engaging said teeth to control the outward sliding movement of the first plate while permitting the latter to slide inwardly; a rotatable cam action disc arranged in the circular hole in said second plate; a finger operated member extending to the casing exterior and connected with

5 said disc whereby the latter may be rotated and the second plate advanced into cap-binding position, said member also extending through an opening in said pawl to pivotally maintain the latter in place; and a pin projecting from said pawl and disposed through the casing slot whereby the pawl may be moved out of engagement with said teeth and the first plate permitted to slide outwardly.
